UNITED STATES PATENT OFFICE

HARRY M. BURT, OF EDGEWOOD, RHODE ISLAND

DESIGN FOR A SALT OR PEPPER SHAKER

Application filed January 21, 1932. Serial No. 42,578. Term of patent 7 years.

To all whom it may concern:

Be it known that I, HARRY M. BURT, a citizen of the United States, residing in Edgewood, county of Providence, and State of Rhode Island, have invented a new, original, and ornamental Design for a Salt or Pepper Shaker, of which the following is a specification, reference being had to the accompanying drawings forming a part thereof.

Fig. 1 is a perspective view of a salt or pepper shaker showing my new design; and Fig. 2 is a top plan view of the same.

I claim:

The ornamental design for a salt or pepper shaker, substantially as shown.

HARRY M. BURT.
